UNITED STATES PATENT OFFICE.

CHARLES ALGERNON PARSONS AND JOHN HUTTON ARMSTRONG, OF NEWCASTLE-UPON-TYNE, ENGLAND; SAID ARMSTRONG ASSIGNOR TO SAID PARSONS.

DYNAMO-ELECTRIC MACHINERY.

No. 869,934.

Specification of Letters Patent.

Patented Nov. 5, 1907.

Application filed February 10, 1906. Serial No. 300,483.

To all whom it may concern:

Be it known that we, CHARLES ALGERNON PARSONS and JOHN HUTTON ARMSTRONG, subjects of the King of Great Britain and Ireland, and residing at Heaton Works, Newcastle-upon-Tyne, in the county of Northumberland, England, have invented certain new and useful Improvements in and Relating to Dynamo-Electric Machinery, of which the following is a specification.

Our invention relates to the construction of a field winding for dynamo electric machinery and is especially applicable to windings for compensating for armature reaction.

In Letters Patent No. 791492 dated June 6 1905 of Charles Algernon Parsons and George Gerald Stoney, a compensating winding is described in which the copper conductor in the form of an insulated strip is wound continuously round slots in the pole faces of the field magnets. This method of construction, however, is difficult to carry out in practice on account of the stiffness of the conducting strips, and also on account of the difficulty of placing the strip in the slots or holes in the pole faces.

The object of our invention is to obviate this difficulty and to construct the winding in such a manner that it can be readily and easily placed in position without danger of injuring the insulation of the winding.

The invention consists in making each bar or strip of the winding separate and approximately straight, the ends of these straight pieces being coupled together by suitably attached connecting pieces.

The invention also consists in fixing the compensating winding in position on the pole faces between strips of magnetic material lying parallel with the axis of the armature and attached to the pole faces by bolts or other means.

The invention further consists in an improved coupling between the bars or strips and connecting pieces.

By means of our invention we are enabled to put the winding into place without risk of damage to the insulation and we have also found that by the new construction better ventilation can be provided at the ends for the armature, and for the compensating winding itself.

Referring to the accompanying drawings:—Figure 1 is an end elevation of a four pole dynamo to which our invention is applied, the compensating coils on the lower half being removed; Fig. 2 is a diagrammatic view showing the arrangement of the compensating winding; Fig. 3 is a section through one of the flanged strips of Fig. 1; Fig. 4 is a plan and Fig. 5 an elevation showing the means employed for connecting up the separate parts of the compensating winding.

In the arrangement illustrated the field magnet frame, *a*, is provided with four projecting pole pieces, *b*, on

which the field coils, *c*, are wound in any usual manner. 55

The compensating winding is placed uniformly on the pole faces and comprises four coils having their axes between the polar axes of the field magnets as shown diagrammatically in Fig. 2. The coils are made up of a number of separate copper strips, *d*, joined up at their 60 ends by other copper strips *e*, and are arranged to give electrically the same effect as is given by the winding shown diagrammatically in Fig. 2 in which the coils are placed in series with the armature and so arranged that the current in any particular conductor is opposite to 65

that in the nearest armature conductor when the machine is in operation. The copper strips, *d*, are held on the pole faces by means of flanged strips, *f*, of magnetic material which fit into shallow grooves, *g*, in the pole faces the grooves being parallel to the axis of the armature. The strips, *f*, may be fixed to the pole faces in any convenient manner, as for instance as shown in Figs. 1 and 3 by means of a clamping strip, *h*, fitting over projection, *k*, on the flanged strips, *f*, and bolted to the body of the pole pieces, *b*. The copper strips, *d*, placed 70 between the strips, *f*, are in this manner held firmly on the pole faces and their ends are joined up so as to form a continuous electric circuit surrounding the armature as shown in Fig. 2. This may be effected for instance by flattening the ends of the strips to about half the 75 thickness of their main portions by a die or other suitable means, the connecting strips, *e*, being then joined to the strips, *d*, by bolts and nuts or in another suitable manner. It will be seen that by flattening the ends of the strips a larger area of contact at the joint is obtained. 80

The whole joint may if desired be brazed or soldered together after completion. 85

Having thus described our invention, what we claim as new and desired to secure by Letters Patent is:—

1. In dynamo electric machinery, a field winding comprising a plurality of separate metal strips, pole pieces, grooves in the face of said pieces parallel to the axis of the machine, flanged elements of magnetic material fitting in said grooves, projections on said elements, clamping pieces fitting over the projections, and means clamping 90 said pieces to the machine; as set forth.

2. In dynamo electric machinery, pole pieces, an electrical winding, means fixing said winding to said pole pieces comprising grooves in the face of the pole pieces parallel to the axis of the machine, flanged elements of 100 magnetic material fitting into the grooves, projections on said elements clamping pieces fitting over the projections, and means attaching said clamping pieces to the machine; as set forth.

In testimony whereof we have signed our names to this 105 specification in the presence of two subscribing witnesses.

CHARLES ALGERNON PARSONS,
JOHN HUTTON ARMSTRONG.
